UNITED STATES PATENT OFFICE.

JOHN E. SEBER AND GEORGE H. CHAPLAIN, OF LEAVENWORTH, KANSAS.

INCUBATOR.

Application filed March 6, 1923. Serial No. 633,139.

To all whom it may concern:

Be it known that we, JOHN E. SEBER and GEORGE H. CHAPLAIN, citizens of the United States, residing at Leavenworth, in 5 the county of Leavenworth and State of Kansas, have invented certain new and useful Improvements in Incubators, of which the following is a specification.

This invention relates to incubators in 10 which are placed a large number of eggs and has special reference to means for shifting the trays containing the eggs as the hatching process progresses. One object of our invention is to provide improved means 15 for lowering the trays as they reach successive stages of incubation, and another object of the invention is to provide novel means for tilting the trays as needed and maintaining the trays in each series or column 20 at fixed distances apart. Other objects of the invention will appear in the course of the following description, and the invention resides in a certain novel construction and arrangement of parts which 25 will be particularly pointed out in claims following the description.

The invention is illustrated in the accompanying drawings, in which—

Figure 1 is a central longitudinal vertical section, with parts in elevation, of a 30 portion of an incubator embodying our improvements;

Fig. 2 is a plan view of the same with the top of the incubator removed;

Fig. 3 is a transverse section;

Fig. 4 is a detail sectional elevation of parts of the means for raising and lowering the trays;

Fig. 5 is a detail section on the line 5—5 of Fig. 4;

Fig. 6 is a detail perspective of a locking cap or washer;

Fig. 7 is a detail view showing the parts 45 of a link connection between the trays separated but approximately in their proper relative positions.

The incubator comprises a casing 1 which may be of any desired dimensions and is provided in its sides with the usual doors 50 to permit access to the interior of the trays when eggs are to be removed or placed therein. Extending longitudinally of the incubator at opposite sides of the center thereof are partitions 2 which define a central chamber in the incubator, as shown 55 most clearly in Fig. 3, the said partitions

terminating short of the top and bottom of the casing, as clearly shown. Disposed between the partitions 2 adjacent but spaced from the lower edges thereof is a false bottom or floor 3, the purpose of which will presently appear, and this false floor or bottom may be supported in any convenient or preferred manner. In the bottom 4 of the casing are open-ended nipples 5 60 which furnish restricted inlets for fresh air, and in the top 6 of the casing are similar nipples 7 which provide outlets for a portion of the foul air, these nipples 5 and 7 being disposed between the partitions 2 65 and the sides of the casing, as shown in Fig. 3. In the top of the central chamber are supported fans 8 which may be electrically driven and are so located that the current of air generated by them will be driven 70 downwardly between the partitions 2 so as to strike the sub-floor 3 and be thereby diverted laterally under the edges of the partitions, as will be readily understood. Over each fan 8 in the top of the casing is a 75 cap 9 having an opening 90 through which fresh air may enter the casing, and heating pipes 80 are disposed within and extend the full length of the central chamber 80 between the partitions 2. To support the 85 fans, we provide a ceiling board 81 which extends from end to end of the casing between the planes of the partitions and is provided at proper intervals with openings 82 to receive fan supports each consisting 90 of stout crossed wires 83 having their ends secured upon the supporting ceiling board and their intermediate portions extending across the respective openings. We employ the ordinary fans now on the market 95 equipped with guards 84 and support the fans by merely resting the guards on the wires 83, the current-carrying cable, indicated at 85, being passed through the opening 90. Should a fan become inoperative 100 for any reason, the cap 9 over that fan is removed whereupon the fan may be lifted out through the opening in the top of the casing and another fan substituted without any appreciable loss of time or disturbance 105 of the circulation within the incubator.

The heating pipes 80 form a coil extending along the sides and across the ends of the central longitudinal chamber of the incubator and are connected with a boiler, indicated at 86, which may be of any preferred construction and located at any con-

venient point. The boiler is equipped with a thermostat (not shown) so that the temperature within the incubator will be automatically controlled in the well-known manner.

The trays 10 are disposed in vertical columns or series between the partitions and the respective sides of the casing and are moved downwardly as the incubation progresses. The number of trays in a column will be determined by the dimensions of the incubator casing, but ordinarily five trays in each column will be found most satisfactory. Those trays in which the period of incubation has nearly passed and in which hatching is about to terminate are supported on the bottom 4 of the casing upon fixed rests, as shown at 11. It will now be readily understood that the heat is supplied at the top of the casing and the fresh eggs are placed in the uppermost trays so that these eggs will be subjected to the greatest heat. When the fans 8 are set in motion, a circulation of the air will be created which will drive the same downwardly, as before stated, to the floor 3 where it will be diverted so as to pass over the trays 11 and then upwardly through the columns of trays 10, foul air escaping through the outlets 7 while the greater portion of the heated air will be drawn over the upper edges of the partitions and again driven downwardly through the corridor between the partitions and thence over the trays 11 and up through the trays 10, as before. When the hot air comes into contact with the cooler air entering through the inlets 5, the moisture contained in the air will be condensed so that the desired humidity will be produced.

Upon the sides of the casing at intervals, we secure brackets 12 and 13 in which are journaled the lower and upper ends respectively of a vertically disposed feed screw 14, the upper end of the said screw being equipped with a beveled gear 15 above the bracket 13, as clearly shown. Upon each partition 2 adjacent the lower edge thereof, we secure brackets 16, corresponding to the brackets 12, and upon the upper edge of each partition we secure brackets 17, corresponding to the brackets 13. A vertically disposed feed screw 18 has its ends journaled in the aligned brackets 16 and 17, and upon the upper end of this feed screw is secured a beveled pinion 19. The brackets 13 and 17 are constructed with upstanding arms 20 in which is journaled a transverse shaft 21 equipped with beveled gears 22 which mesh with the pinions 15 and 19, as shown and as will be readily understood. The shafts 21 are extended inwardly beyond the arms 20 of the brackets 17 and are equipped upon their inner extremities with beveled pinions 23 meshing with similar pinions 24 upon the transmission shafts 25 extending longitudinally of the incubator casing.

These shafts 25 may be journaled in any desired manner in the end walls of the casing, and, adjacent one end of the casing, we secure, upon the partitions brackets 26 which provide bearings for a transverse shaft 27 equipped with beveled pinions 28 meshing with pinions 29 on the respective shafts 25. One shaft 25 has its end extended through the adjacent end wall of the casing and is equipped with a crank 30 or other convenient form of turning handle. When the handle or crank 30 is rotated, the shafts 25 will, of course, be also rotated and this motion will be transmitted through the described gearing to the screws 14 and 18, as will be readily understood.

Upon each end of each tray is secured a bracket 31 having a boss 32 at its upper end provided with a central aperture to receive a pivot stud 33 formed on the end of a swivel member 34 whereby the tray may have pivotal movement about the said swivel member. The said member 34 is constructed with a lug 35 which fits between the upper and lower lugs or ears 36 of a split nut 37 and is pivotally connected with the said lugs by a pin or rivet 38 inserted vertically therethrough, as clearly shown in Fig. 4. A spring 39 is fitted about the pivot 35 and bears against suitable abutments or is attached to the members of the split nut so as to hold the nut normally closed and in engagement with the feed screw, as will be readily understood. When the feed screws are rotated, the nuts will be caused to travel longitudinally thereof and, consequently, will effect vertical movement of the trays so that they may be raised or lowered as desired. To further aid in holding the nuts in engagement with the feed screws 18, we provide the tubular guiding and retaining casings 40 which consist of split sleeves secured in any desired manner to the partitions 2 and encircling the feed screws, the split or slot 41 in the sleeve providing a passage through which the shanks or stems of the split nuts may pass. The slot 41 should be just wide enough to permit the shanks or necks of the nuts to slide freely therein and at the same time should fit so closely to the nuts as to prevent them from opening when the screws are rotated. The screws 14 mounted upon the sides of the casing are not disposed within tubular guide housings, but the nuts engaging the same are held against premature or undue opening and consequent release by locking washers or caps 42 which are provided with radial slots or notches 43 in their tops or webs 44 so that they may be easily fitted about the screw and are constructed with rims 45 adapted to fit closely about the heads and edges of the nuts and thereby prevent opening of the

same. It will now be readily noted that the trays will be caused to move vertically by the rotation of the screws and, therefore, the trays may be caused to descend at intervals as the incubation progresses so that those eggs which are about ready to hatch and do not need so much external heat will be gradually brought to the bottom of the incubator, while the fresher eggs which need a greater amount of external heat will be located near the top of the casing where the heat is supplied. When a tray is inserted in the incubator, it is pushed against the feed screw 18 above the threads thereon so that the split nut will open and pass around the smooth surface of the screw, after which the tray is lowered until the nut passes within the open end of the sleeve 40 and engages the threads of the screw. The nut at the outer end of the tray is closed around the threads of the feed screw 14 and the locking cap 42 is engaged over the nut to hold it in engagement with the threads. The member 18 is smooth above and below the sleeve 40 to facilitate the engagement and withdrawal of the nut but the member 14 is threaded to its end so as to retain its engagement with the nut and prevent precipitate dropping of the lowermost tray.

It is desirable to vary the position of the eggs at intervals as well as to move them away from the point of greatest heat. To accomplish this shifting of the eggs, we provide means for tilting the trays in each column, said means consisting of links pivotally attached to and connecting the trays in each column, and means for imparting vertical movement to the links whereby the trays will be turned about their pivotal supports 33. The links 46 each consists of an upper narrow strap or member 47 pivoted at its upper end upon the side of the tray and provided at its lower end with a notch 48 adapted to receive a securing screw or pin 49 inserted through an opening 50 in the lower strap or member 51. The screw 49 is inserted through the opening 50 and the notch 48 and a thumb nut 52 is mounted upon the end of the screw and turned home against the link member 47 so as to hold the links securely in alinement, and to further maintain the alinement of the link members, the lower member is extended above the connecting screw 49 and equipped with lugs 53 at its edges adapted to enter notches 54 formed in the side edges of the upper member 47. It will, of course, be understood that the lower end of the member 51 is pivoted to the side of a tray and the upper end of a subjacent member 47 is pivoted to the same tray by the same pivot pin or rivet. Pivotal movement of the trays is thus permitted but the equidistant spacing of the trays is maintained whether the trays be disposed horizontally or inclined in either direction. One of the links 46 is extended above the column of trays and has its upper end pivoted to an angle lever 55, which lever is, in turn, pivoted at its upper end to a connecting rod 56 extending longitudinally of the casing adjacent the side thereof. Disposed transversely within the casing at any convenient point is a rock shaft 57 equipped at its ends with cranks 58 which project upwardly and are pivotally connected to the respectively adjacent connecting bars 56. At the center of the said rock shaft 57 is a double crank or rocking arm 59, to the ends of which are pivotally attached links or pitmen 60 which extend to a point adjacent the end of the incubator casing and are there connected to the lateral terminals of an angle lever 61 which is carried by a bracket 62 secured upon the outer casing, the handle member 63 of the said lever projecting through a slot 64 provided therefor in the end wall of the incubator casing, as shown clearly in Fig. 1. If the handle 63 be swung upwardly or downwardly, a corresponding movement will be imparted to the lateral arms of the lever 61 which will be transmitted through the pitmen 60 to the double crank 59 and the shaft 57 will be thereby rocked. The rocking of the shaft 57 will be transmitted through the cranks 58 to the connecting bars 56 so that the angle levers 55 will be, in turn, rocked and a vertical movement transmitted through the several links 46 to the trays 10 so that they will be tilted about their pivotal supports 33 and the desired shifting of the eggs accomplished.

From the foregoing description, taken in connection with the accompanying drawings, it will be seen that we have provided a very simple apparatus in which a large number of eggs may be successfully treated, the working parts being simple in construction and compact in arrangement so that they may be easily manipulated and are not apt to get out of order. The fresh eggs are placed in trays at the tops of the several columns or series of trays and, as the incubation period passes, the trays will be successively fed downwardly by rotation of the feeding screws, as will be readily understood and as has been stated. When a tray reaches the bottom of a column, the split nuts carrying said tray will come into contact with the brackets 16 and further downward movement of the tray will be, therefore, arrested so that the tray may then be removed, after the link 46 is disconnected, and supported on the fixed rests on the floor 4, as shown at 11. The air within the incubator will be caused to pass across the eggs which are about ready to hatch so that these eggs will not be overheated but will be prevented from chilling and causing a loss of the fowls. The heated air passing over

4

these lowermost trays will create a suction through the inlets 5 so that some fresh air will be drawn into the incubator and this fresh air, being cooler, will cause condensation of the moisture in the heated air so that a humid air will pass up through the trays in the several vertical series or columns and circulate about the eggs in said trays mingling with the hotter air immediately adjacent the top of the casing and being then drawn over the upper edges of the longitudinal partitions by the fans. The heat is thus supplied to the eggs according to the condition of the eggs and proper incubation is insured. Of course, as the conveyers or feed screws are operated to cause descent of the trays, the trays will be tilted to assume a reverse inclination inasmuch as the links 46 are attached nearer the sides of the trays or eccentric to the pivotal supports of the trays. More frequent turning of the trays is effected by manipulation of the lever 63. When a fresh tray is placed in position at the top of the column, the top links must, of course, be disconnected and then connected to the inserted tray which in turn is connected with the adjacent angle lever 55. The sectional construction of the links facilitates this adjustment.

30 Having thus described the invention, what is claimed as new is:

1. In an incubator, trays arranged in a vertical series and supported for pivotal movement, links pivoted to and connecting the trays, an endwise movable connecting bar, and angle levers connecting said bar with the said links.
2. In an incubator, trays arranged in a vertical series and supported for pivotal movement, links pivoted to and connecting the trays, an endwise movable bar, angle levers connecting said bar with the links, a rock shaft, a crank on said rock shaft pivoted to said bar, and means for rocking said shaft.
3. In an incubator, trays arranged in vertical series and supported for pivotal movement, links connecting the trays, means for moving said links vertically whereby to tilt the trays, said links each consisting of an upper member having notches in its side edges, a lower member provided at its upper end with lateral lugs to engage said notches,

and means for detachably connecting the said members, the upper member being pivoted to an upper tray at its upper end and the lower member being pivoted at its lower end to a lower tray.

4. In an incubator, trays arranged in a vertical series, vertically disposed feed screws adjacent the ends of the trays, nuts engaging said screws, pivotal connections between the nuts and the trays, and means for rotating said screws.

5. In an incubator, trays arranged in a vertical series, vertical feed screws disposed adjacent the ends of the trays, split nuts adapted to be engaged around the feed screws and pivotally supporting the trays, means for rotating the feed screws, and means for retaining the split nuts in engagement with the screws.

6. In an incubator, trays arranged in vertical series, vertically disposed feed screws adjacent the ends of the trays, bracket members provided with studs pivotally engaging the ends of the trays to support the same, split nuts mounted on said brackets and adapted to engage the feed screws, means for retaining said nuts in engagement with the feed screws, and means for rotating the screws.

7. In an incubator, trays arranged in a vertical series, vertically disposed feed screws arranged adjacent the ends of the trays, split nuts engaging the feed screws, brackets carrying said nuts and pivotally engaging and supporting the trays, guide tubes encircling some of the feed screws and having vertical slots receiving the necks of the split nuts whereby to maintain the nuts in engagement with the screws, and means for rotating the screws.

8. In an incubator, trays arranged in a vertical series, feed screws arranged adjacent the ends of the trays, nuts engaging the screws and pivotally supporting the trays, beveled gears on the upper ends of the screws, a transverse shaft, beveled gears on said shaft meshing with the gears on the respective screws, and means for rotating said shaft from an end of the incubator.

In testimony whereof we affix our signatures.

JOHN E. SEBER. [L. S.]
GEORGE H. CHAPLAIN. [L. S.]
